(57) **CLAIM**

The ornamental design for a FILTER CARTRIDGE as shown and described.

DESCRIPTION

FIG. 1 is a perspective view of a filter cartridge.
 FIG. 2 is a top view of the filter cartridge of FIG. 1.
 FIG. 3 is a bottom view of the filter cartridge of FIG. 1.
 FIG. 4 is a side view of the filter cartridge of FIG. 1.
 FIG. 5 is an end view of the filter cartridge of FIG. 1.
 FIG. 6 is an opposite end view of the filter cartridge of FIG. 1.
 The broken lines depict portions of the filter cartridge that form no part of the claimed design.

1 Claim, 4 Drawing Sheets
